AUTOMATIC LETOFF CONTROL

Yervant H. Kurkjian, Clifton, N. J.

Application March 2, 1943, Serial No. 477,743

4 Claims. (Cl. 139—107)

This invention relates to an automatic control for the let-off mechanism of looms, and the like, and has for one of its objects the production of a simple and efficient automatic let-off control which will control the tension of the brake band of the warp beam in a proper manner to maintain a uniform tension of the warp threads carried by the warp beam.

A further object of this invention is the production of a simple and efficient means for automatically shifting the position of the control weight relative to the brake band of a warp beam in a manner to retain a uniform tension upon the warp threads carried by the beam.

Other objects and advantages of the present invention will appear throughout the following specification and claims.

In the drawings:

Figure 1 is a side elevational view of one form of the automatic let-off control;

Figure 2 is a fragmentary front elevational view of one end thereof;

Figure 3 is a side elevational view of a modified form of the invention;

Figure 4 is a fragmentary front elevational view of one end of the structure shown in Figure 3;

Figure 5 is a side elevational view of a further modified form;

Figure 6 is a side elevational view of a still further modified form;

Figure 7 is a fragmentary side elevational view of another modified form of the invention;

Figure 8 is a fragmentary sectional view taken on line 8—8 of Figure 7;

By referring to the drawings, it will be seen that 10 designates the frame of the loom of a conventional type, which carries the warp beam 11 also of the conventional type. Since the present invention relates to the automatic let-off control mechanism and not to the general loom construction, no effort is made to illustrate the detail construction of the loom itself, and only those parts vital to the invention are illustrated and described.

A tension control arm 12 is pivoted at its lower end 13 to the frame 10, as shown in Figures 1 and 2. This arm 12 carries a warp contact roller 14 at its upper end for direct contact with the warp threads which are wound upon the warp beam 11, or the threads upon a spool, as the case may be. A leverage control link 15 is pivotally connected, as at 16, to the arm 12, by means of a journal extending through the slot 17 formed in the frame 10. This link 15 carries a pair of

transverse rollers 18 and 18^a arranged one above the other at the outer end of the link 15, as shown in Figure 1. A tension spring 19 is connected at one end 20 to the frame 10, and at the other end 21 to the outer roller-carrying end of the link 15—see Figure 1.

A conventional flexible brake band 22 passes around the conventional brake drum 23 and is anchored at one end to the frame 10, as at 24.

10 The brake band 22 is connected at its opposite end to the outer end 25 of the brake lever 26. The brake lever 26 is pivoted to the frame 10 by means of a pivot 27. The inner end 28 of the brake lever 26 overlies and contacts the upper roller 18 of the link 15.

An intermediate lever 29 is pivoted, as at 30, to the frame 10, and the outer end 31 contacts the under face of the lower roller 18^a of the link 16. The downwardly offset inner end 32 of the intermediate lever 29 fits under a transverse pin 33 carried by the weight lever 34. This weight lever 34 is pivoted to the frame 10, as at 35. The lever 34 underlies the lever 29 and carries an adjustable weight 36 at its outer free end. The

20 weight 36 may be adjusted as to weight by adding additional weight plates and may be adjusted as to position by movement relative to the adjusting notches 37 formed upon the weight lever 34.

25 30 By considering Figure 1, it will be seen that as the lever 12 swings toward the center of the beam 11, and as the warp is unwound, the position of the rollers 18 and 18^a will be shifted upon the levers 26 and 29, the roller 18 moving toward the pivot 27 and the roller 18^a moving away from the pivot 30. The intermediate lever 29 is provided with a rocking contact with the pin 33 of the weight lever 34. As the leverage is shifted by the changing position of the rollers 18 and 18^a

35 40 relative to the levers 26 and 29, as a result of the movement of the arm 12, the tension of the brake band 22 will be decreased in proportion to the weight of the weight 36 and the shifting leverage caused by the shifting of position of the rollers

45 45 18 and 18^a relative to the levers 26 and 29. Consequently, as the warp is unwound from the beam 11, the brake band 22 will be loosened due to the shifting leverage and in this manner the warp will at all times be kept substantially at a uniform tension. The tension of the brake band 22 will be regulated in ratio to the inwinding of the warp, the position of the tension control arm 12, and the leverage differential between the levers 26 and 29 occasioned by the shifting of the

50 55 rollers 18 and 18^a carried by the link 15. In this

form of the invention; the weight 36 remains in a selected position and the pull of the weight 36 upon the brake band 22 is adjusted by the shifting leverage interposed between the weight 36 and the brake band 22. The decreased leverage is provided as the size of the warp reduces and permits the arm 12 to swing toward the beam 41, thereby moving the roller-carrying end of the link 15 toward the pivot 27 and away from the pivot 30. In the form shown in Figure 1, it should be noted that the compound leverage arrangement is located directly below the warp and is confined within the area of the frame 10. The weight lever 34 is pivoted near the front of the frame 10 and the free end of this weight lever 34 extends back under the intermediate lever 28 thereby avoiding any protruding parts beyond the front of the frame 10.

By referring to Figures 3 and 4 it will be seen that a modified form of the invention is disclosed, wherein a frame 40 is illustrated of a conventional type, and a warp beam 41 is supported in a relative position to the frame 40 in any suitable or desired manner. The warp beam 41 carries a suitable brake drum 42 over which passes a brake band 43 of any suitable type, which band 43 is anchored at one end as at 44, to the frame 40, and the opposite end is secured to the outer end 45 of the brake lever 46. This brake lever 46 is pivoted as at 47 to the frame 40. A control arm 48 is journaled, as at 49, upon the frame 40 and this control arm 48 carries a warp contact roller 50 at its upper end for contacting the warp threads wound upon the beam 41. The journal 49 which is keyed to the arm 48 carries a gear wheel 51, which gear wheel meshes with a rack 52 formed upon the under face of the weight lever 53.

The weight lever 53 supports a hanging weight 54 of a suitable type in a selected adjusted position, the weight 54 being suitably adjusted with respect to the notches 55 formed upon the upper face of the weight lever 53. This weight lever 53 is suitably guided through suitable guiding brackets 56 of any desired type. The weight lever 53 is provided with a pair of upstanding ears 57 between which ears is rotatably mounted a contact roller 58, the contact roller 58 engaging at all times the under face of the brake lever 46, the ears 57 extending upwardly and spanning the lever 46 to hold the roller 58 in contacting position with the lever 46.

A suitable compression spring 59 is adjustably carried by brackets 60 and contacts the arm 48 to normally hold the roller 58 of the arm 48 in contacting relation with respect to the warp wound upon the beam 41. As the warp is unwound from the beam 41 in the direction of the arrow indicated in Figure 3, the roller 58 will move inwardly toward the center of the beam 41 thereby rotating the gear 51 in a counterclockwise direction and shifting the weight lever 53 in the direction of the arrow and thereby moving the roller 58 toward the pivot 47 and shortening the leverage upon the brake lever 46. Consequently, as the warp is unwound from the beam 41 the roller 58 will follow the warp as it reduces in diameter upon the beam 41 and consequently, the tension of the brake band 43 will be gradually and automatically decreased due to the shifting of the leverage which will naturally decrease the weight pressure upon the brake lever 46 and in this manner as the warp is withdrawn or unrolled from the beam 41 the tension of the brake band 43

will be automatically reduced in ratio to the amount of warp unrolled from the beam 41, and thereby permit the warp to remain at all times at a substantially uniform tension, the control being regulated by the contact of the roller 58 with the warp which is wound upon the beam 41.

By referring to Figure 5 it will be noted that I have shown a still further modified form wherein the frame 61 is illustrated and a warp beam 62 is supported in any suitable or desired manner above the frame 61. A brake band 63 is anchored at one end, as at 64, to the frame 61, and the opposite end of the brake band 63 which passes over the brake drum 65 is connected, as at 66, to the outer end of the brake lever 67. The brake lever 67 is pivoted as at 68, and the opposite end of the brake lever 67 is provided on its under face with rack teeth 69 for meshing with a movable pinion 70 slidably mounted within a suitable guide 71 carried by the inner end 72 of the weight lever 73.

A control arm 74 is pivoted at its lower end 75 to the frame 61 and this arm 74 is pivotally connected, as at 76, to the weight arm 73. The inner end 72 of the weight arm 73 is provided with rack teeth meshing with the movable pinion 70 and the arm 74 is provided with an extension which carries a warp contact roller 77. The warp contact roller 77 is adapted to contact the warp which is wound upon the beam 62 and operates in a manner similar to that previously described, in the other forms. A suitable tension spring 78 engages the arm 74 to normally hold the arm 74 in an operative position to press the roller 77 against the warp which is wound upon the beam 62. As the arm 74 swings in toward the beam 62 in the direction of the arrow, the weight beam 73 will also be moved in the direction of the arrow indicated on the beam and the movable pinion 70 will be moved toward the pivot 68 of the brake lever 67 shortening the leverage and automatically reducing the tension of the brake band 63 in ratio to the swing of the arm 74 and in this way keeping the warp which is being unwound from the beam 62 at substantially uniform frame tension.

In Figure 6, there is shown another modified form of the invention wherein a frame 79 is illustrated and a beam 80 of a suitable type is supported above the frame 79, the rotation of the beam being controlled by a brake band 81 which is anchored, as at 82, at one end, and is connected as at 83 at its opposite end to the brake lever 84. This brake lever 84 carries a control arm 85 which is pivoted as at 86, and this arm 85 carries a warp contacting roller 87 at its upper end for contacting with the warp which is rolled on the beam 80. The lower end of the control arm 85 carries a roller 88 which contacts with the outer end 89 of the weight lever 90, and this weight lever 90 is pivotally connected, as at 91, to the frame 79. A drum 92 is also carried near the lower end of the control lever 85 and over the drum 92 passes a flexible cable 93 which cable is anchored as at 94 at one end and is connected to a sliding weight carriage 95 at its opposite end. As the warp is unwound from the beam 80, the roller 87 by contacting with the warp upon the beam 80 will permit the control lever 85 to swing inwardly toward the beam thereby moving the roller 88 outwardly in the direction of the arrow on the beam 90, and this movement will cause the cable 93 to pull the sliding weight carriage 95 inwardly and consequently reduce the tension of the brake band 81 upon the brake drum 80 in ratio to the amount of warp which

has been unrolled or unwound from the beam 80.

As shown in Figures 7 and 8, a still further modified form of the invention is illustrated wherein a frame 96 is illustrated above which is mounted a conventional warp-supporting beam 97 upon which the warp 98 is wound. A brake drum 99 is carried by the beam 97 and a brake band 100 is anchored, as at 101, at one end to the frame 96 and is secured as at 102 at its opposite end to the brake lever 103. This brake lever 103 is pivoted as at 104 upon the frame 96 and carries a link 105 at its opposite end which link is pivotally connected to the inner end 106 of the weight lever 107, this lever 107 being pivoted as at 108 upon the frame 96.

A weight 109 is adjustably mounted in a selected position upon the weight lever 107 and a spring-pressed contact roller 110 is pivotally supported upon the lever 107 for contact with the warp 98 wound upon the beam 97. As the warp 98 is wound from the beam 97, the roller 110 will be moved to the dotted position shown in Figure 7, reducing the pressure upon the weight beam 107 and also reducing the tension of the brake band 100 upon the brake drum 99 in a manner similar to that described in the foregoing forms.

It should be understood that certain detail changes in the structure illustrated may be employed without departing from the spirit of the invention and it should be borne in mind that the important feature of the present invention is the means for automatically controlling the tension of the brake band in ratio to the amount of warp which is unwound from the supporting beam thereby keeping the warp at a constant or substantially uniform tension.

Attention is directed to my co-pending application Serial No. 504,180, filed September 28, 1943 relating to Control for let-off mechanism of looms, which is a continuation in part of this application; and to application Serial Number 504,181, filed September 28, 1943, now Patent No. 2,355,656, relating to Automatic control for let-off mechanism of looms; and to application Serial Number 504,182, filed September 28, 1943, now Patent No. 2,357,336, relating to Automatic control for the let-off mechanism of looms, the latter two applications being divisions of the instant application.

Having described the invention, what is claimed is:

1. An automatic let-off control mechanism of the class described comprising, a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a swinging warp-

engaging arm, a pressure lever engaging said brake lever to one side of said pivot, and a rack and pinion connection between said pressure lever and said warp-engaging arm for shifting the pressure lever relative to the brake lever as said warp-engaging arm swings.

2. An automatic let-off control mechanism of the class described comprising, a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a rack carried by the brake lever, a pivoted warp-engaging arm, a weight arm pivoted to the warp-engaging arm, a rack carried by the weight arm, and a pinion contacting the racks and movable therebetween.

3. An automatic let-off control mechanism of the class described comprising a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a swinging warp-engaging arm, a pressure lever mounted adjacent the brake lever, means connecting the pressure lever with said warp-engaging arm for shifting said pressure lever relative to said brake lever as said warp-engaging arm is swung, and contact means interposed between the brake lever and pressure lever located to one side of the pivot of said brake lever and shiftable as said pressure lever is shifted by the swinging of said arm to vary the leverage of said pressure lever upon said brake lever in proportion to the amount of warp which is carried by said beam.

4. An automatic let-off control mechanism of the class described comprising a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a shiftable pressure-creating means contacting the brake lever at a point spaced from said pivot, a swinging warp-engaging arm, and automatic means interposed between the brake lever and warp-engaging arm for shifting the position of the pressure-creating means relative to said pivot in ratio to the movement of said warp-engaging arm and the amount of warp unwound from said beam in a manner whereby the tension upon the brake drum will be proportionately reduced as the warp is let off to thereby maintain a constant uniform tension upon the warp while the warp is being let off.

YERVANT H. KURKJIAN.
